(57) **CLAIM**

The ornamental design for an electronic housing, as shown and described.

DESCRIPTION

FIG. 1 is a front perspective view of an electronic housing showing our new design;

FIG. 2 is a top view thereof;

FIG. 3 is a bottom view thereof;

FIG. 4 is a front view thereof;

FIG. 5 is a rear view thereof;

FIG. 6 is a left side view thereof; and,

FIG. 7 is a right side view thereof.

The broken line showings of elements in FIGS. 1-7 are for illustrative purposes only and form no part of the claimed design.
